UNITED STATES PATENT OFFICE.

CHARLES S. ELLIS, OF CHICAGO, ILLINOIS.

ELECTRIC TIME-STAMP.

1,213,345.

Specification of Letters Patent. Patented Jan. 23, 1917.

Application filed March 10, 1911. Serial No. 613,617.

To all whom it may concern:

Be it known that I, CHARLES S. ELLIS, a citizen of the United States, and a resident of Chicago, in the county of Cook and State 5 of Illinois, have invented certain new and useful Improvements in Electric Time- Stamps; and I do hereby declare that the following is a full, clear, and exact description thereof, reference being had to the accompanying drawings, and to the characters of reference marked thereon, which form a part of this specification.

This invention relates to a novel portable hand electric time stamp having a handle 15 by which it is manipulated in the manner of an ordinary hand stamp and provided with movable time marking elements arranged in such relation to a marking or printing dial as to impress upon a paper or 20 the like the exact time of its receipt by a person or in a department of business, and carrying suitable magnetically actuated clock mechanism for operating the movable time marking elements that is adapted to be 25 operated by a suitable electric connection with an electric clock or other suitable electric device for intermittently advancing the movable time marking elements.

Among the objects of the invention is to 30 provide an exceedingly simple, efficient and compact stamp of this character which may be made at relatively small cost and which may be used in the manner of an ordinary hand dating stamp, and also to provide a 35 master clock controlled stamp of this character comprising a casing having at its lower side a marking or stamping die, including the moving, time controlled marking elements and at its upper side a dial traversed 40 by an hour and a minute hand connected to the same arbor or staff by which the time marking elements are moved so that the device becomes a convenient clock on the desk.

A further object of the invention is to 45 improve and simplify the magnetically actuated mechanism for operating the time marking elements.

As shown in the drawings, Figure 1 is a bottom plan view of a hand stamp embodying my invention. Fig. 2 is a bottom plan view of the mechanism with the bottom half of the casing removed. Fig. 3 is a section on the line 3—3 of Fig. 2. Fig. 4 is a de-

tail of the magnetically operated pawl and ratchet mechanism for giving movement to the hour and minute hand trains. Fig. 5 is a plan view of the stamp casing.

As shown in the drawings, the casing of the stamp comprises an upper member 10 having a surrounding flange 11, and a lower member 12 having a similar flange 13, the latter flange 13 being adapted to fit in telescopic relation to the flange 11 and to be attached together by the screws 14. The casing is herein shown as made rectangular but it may be made of other shape. The upper member 10 of the casing is cut away to provide an opening which is surrounded by a bevel flange 16 to receive and hold in place a familiar form of crystal 17 through which a watch dial 18 below may be observed as hereinafter described. A forked sheet metal handle, comprising the members 20, 20 is arranged to straddle the casing and to be secured to the flange 11 of the upper member 10 by the rivets 21; and the screws 14 by which the casing members are fastened together also extend through said handle members. The said handle members 20 may terminate in a suitably shaped hand piece, not herein shown.

Attached to the bottom member 12 of the casing is a yielding base 25 preferably made of india rubber, which in turn supports an annular marking dial 26 fixed in any suitable manner thereto, said marking dial bearing thereon the figures 1 to 12 arranged, as viewed from below, in the reverse order of the figures on a clock dial. The said base 25 and the marking dial 26 are arranged with central openings 27 and 28 to coincide with an opening 29 in the lower casing member 12, and it is through these openings that the time controlled marking hands or members extend from their actuating mechanism in the casing with their lower ends substantially in the plane of the lower face of the marking dial 26.

Referring now to the electrically operated clock mechanism within the casing for actuating the movable time marking elements referred to, and for simultaneously moving the hands which traverse the dial 18, said parts are made as follows:—32, 33 designate upper and lower pillar plates that are rigidly connected by the pillars 34. The said

connected plates are attached to and are carried by the upper frame member through the medium of screws 35, and are spaced from the upper member by spacing sleeves 5 surrounding said screws. The upper pillar plate 32 carries a dial supporting plate 36 by which to support the dial 18 before referred to.

40 designates the minute hand arbor 10 which is arranged centrally of the clock movement frame. At its upper end said arbor 40 carries a minute hand 41 which traverses the dial 18, said hand being fixed on the arbor. Loosely mounted on the arbor 15 between the upper frame plate 32 and the dial plate is a gear wheel 42 which is provided with an elongated hub 43 that extends through the dial plate and dial, and to the outer end of which is attached the 20 hour hand 44 which traverses the dial 18. The said hour hand gear wheel 42 is driven from the arbor 40 through the medium of a pinion 45 fixed thereon, the gear wheel 46 meshing with said pinion and a pinion 25 47 carried by the latter gear wheel and meshing with said minute gear wheel. The said minute hand arbor carries at its lower end a time marking element or die 50, made of rubber or like yielding material, arranged with its free end in the plane of the lower face of the dial stamp die 26, and by which to mark the minutes. The said 30 minute marking element consists of an elongated finger having a base portion 51 that is clamped in any suitable manner, as by prongs, to a disk 52 that is fixed to the lower end of the minute hand arbor.

53 designates a gear wheel having a hub 54 which is loosely mounted on the minute 40 hand arbor above the hub of the disk 52. Said gear wheel 53 is driven from the minute hand arbor by means of a pinion 55 fixed to the arbor, a gear wheel 56 meshing therewith and a pinion 57 fixed centrally to the latter gear wheel and meshing with the gear wheel 53. The hub 54 of the gear wheel 53 carries a disk 59 which is provided with holding spurs, or other suitable holding means 60 by which to hold 45 in place a second time marking element or die 63 to indicate the hours; said latter time marking element revolving about the central time marking element 50. The said disk 59 may be supported, when stamping pressure is brought on the device, by an annular flange or ring-like member 64 attached thereto and bearing against the frame member 33 and cut away at one side to receive the gear wheel 56 and pinion 57.

60 The minute hand arbor is arranged to be given an intermittent movement through the action of a magnet within the casing that is controlled from an electric clock or other make and break electric device. As 65 herein shown the means for transmitting a

step by step movement to the minute hand arbor is made as follows:—66 designates a ratchet disk which is loosely mounted on the minute hand arbor 40.

67 designates a collar fixed to the arbor, 70 and between said collar and a washer 67 frictionally engaged with said ratchet disk 66 is interposed a spiral compression spring 68, whereby said ratchet disk is frictionally connected to the arbor in a manner to transmit 75 rotary movement to the arbor, but to permit the arbor to be turned therein to set the hands and the time marking elements. The said ratchet disk is herein shown as provided with sixty ratchet teeth and, with 80 this arrangement, the electromagnet mechanism will be arranged to advance the disk the space of one tooth once each minute so as to turn the arbor once each hour; the hour hand wheels 42 and 53 being geared to rotate one twelfth the distance of the arbor in each intermittent rotative movement of the latter. The said ratchet disk is thus intermittently turned or rotated through the action of a pawl 70 that is pivoted at one end to one end of a swinging lever 71, pivoted at 72, to the top pillar plate 32 and arranged beneath said plate 32. Said lever 71 is provided near its pawl carrying end with a downturned flange 73, to which is attached an iron plate 74 that constitutes the armature for an electromagnet 75 arranged within the casing adjacent thereto. A spring 76 which is attached to a lug 77 of the pawl carrying arm 71 bears 90 at one end against one of the pillar posts 34, as shown in Figs. 2 and 4, and normally holds the pawl carrying lever in its forwardmost position. The free end of the pawl 70 is held engaged with the teeth of the disk 66 by means of a spring 79, engaging at one end the outer side of said pawl between its pivot and its free end and attached at its other end to a stud 80 on the pawl carrying lever. 95

100 When the magnet 75 is energized the arm 71 is drawn toward the magnet, or away from the axis of the ratchet disk 66, thereby carrying the pawl 70 out of engagement with one of the teeth of said ratchet disk and into engagement with the next rear tooth. When the magnet is deenergized the spring 76 acts on the lever 71 to swing it toward the axis of the ratchet disk and the spring 79 of the pawl acts during this 115 time to hold the pawl engaged with a tooth of the ratchet disk so as to advance the said disk one step in its rotation and to thereby act through the minute arbor 40 to advance the hour and minute hands and marking 120 elements. As before stated when the disk is provided with sixty teeth, said disk is adapted to be stepped forward in the manner described once each minute, the circuit of the magnet 75 being closed by suitable 125 130

circuit closing devices located, as for instance, in or constituting part of an electric clock (not shown).

The movement of the pawl carrying arm 5 71 under the influence of the spring 76 is arrested by means of a stop lug 82, which is shown as struck downwardly from the pillar plate 32. Located adjacent to the periphery of the ratchet disk 66 is a lug 10 83 which is shown as being struck down from the plate 32, and between which and the toothed periphery of the ratchet disk the free end of the pawl 70 extends. The 15 location of the lug 83 is such with respect to the free end of the pawl and the ratchet disk 66 that when the pawl is in its forward-most position the said lug 83 prevents the release of the pawl from the ratchet disk in such manner that said disk may not be 20 turned in either direction. The disk is held from backward rotation at a time when the pawl 70 is riding backwardly over the teeth thereof by means of a holding dog 84 pivoted to the plate 32 and pressed against 25 the toothed disk by means of a spring 85.

The circuit wires 86 of the magnet circuit are led into the casing through a nipple 88 fixed in any suitable manner to a flange 89 struck down from the margin of the 30 upper pillar plate 32, as shown in Fig. 2, said wires being connected to the coil in any suitable or preferred manner. The wires pass through a flexible tube 90 just outside of the nipple 88 to give proper 35 flexible connection of the wires with the casing, without permitting said wires to bend too sharply so as to break them.

At one or both sides of the marking dial is arranged channels to receive a line or 40 lines of type. For instance, at one side of said dial may be arranged a permanent line 92 of type, such, for instance as the word "Received", while at the other side of the

base may be arranged a groove 93 to receive a composed line of type, such as a date, 45 which may be changed from day to day.

I claim as my invention:—

A hand electric time stamp adapted to be actuated from a master clock, comprising a casing of less height than width and consisting of top and bottom detachably connected members with means for detachably connecting them, a hand piece attached to the top member, connected upper and lower pillar plates within the casing to constitute 50 a unitary frame removably attached to and carried by the upper casing member, a yieldable dial stamping die carried by the bottom casing member and provided with a central opening, a clock dial carried by the 55 upper pillar plate below the hand piece, an arbor rotatively mounted in and arranged concentrically of the removable frame, hour and minute hands traversing the clock dial and connected to and operated by said arbor, yieldable hour and minute marking dies 60 extending into the central opening of the stamp die with their lower faces in the plane of the lower face of said latter die and connected to and operated from the 65 arbor, pawl and ratchet mechanism carried by said frame for giving intermittent rotation to said arbor, and a horizontally arranged electro-magnet within the casing at one side of the arbor and mounted on the removable frame for actuating the pawl and ratchet mechanism.

In testimony that I claim the foregoing as my invention I affix my signature in the presence of two witnesses, this 7th day of 80 March, A. D. 1911.

CHARLES S. ELLIS.
